His Attorney.

UNITED STATES PATENT OFFICE.

OSCAR C. SCHMIDT, OF CINCINNATI, OHIO, ASSIGNOR TO THE CINCINNATI BUTCHERS' SUPPLY COMPANY, OF CINCINNATI, OHIO, A CORPORATION OF OHIO.

PRESS HEAD FOR STUFFING MACHINES.

Application filed September 6, 1927. Serial No. 217,754.

The press-head to which my invention relates is particularly applicable for employment in so-called stuffing machines for stuffing sausage casings and for other purposes 5 in the meat industry. In mechanism of this character a cylinder is employed in which the press-head is caused to reciprocate by fluid pressure applied to the lower end of the press-head and by release of said pressure. The 10 pressure is applied to the lower end of said press-head for communicating pressure to the plastic material in the cylinder above the press-head to cause the plastic material to be exuded or pressed through suitable nozzles into sausage casings or containers. The 15 compressed fluid employed is usually compressed air or water.

It is important in devices of this character that none of the compressed fluid shall pass 20 the press-head into the plastic material, and that none of the juices from the plastic material shall pass the press-head.

I have provided a press-head of novel construction by means of which these desirable 25 objects are obtained, and a press-head which is of simple construction, which permits ready adjustment to accommodate for pressures employed and for wear and deterioration of materials, and which is comparatively 30 light while capable of successfully resisting great strains in operation.

The invention will be further readily understood from the following description and claims, and from the drawings, in which:

35 Fig. 1 is an axial vertical section of my improved press-head in connection with so much of a stuffing machine as is necessary to disclose its structure and functions.

40 Fig. 2 is a horizontal cross-section of my improved device, taken in the plane of the irregular line 2—2 of Fig. 1.

Fig. 3 is a plan view of a detail, partly 45 broken away, showing the adjusting means between the sections of the press-head; and,

Fig. 4 is a bottom view of the upper section of the press-head, partly broken away.

The cylinder of the stuffing machine is exemplified at 11. A press-head 12 is arranged 50 to reciprocate in said cylinder in suitable manner, as by means of pressure applied by compressed fluid in the pressure end 13 of the cylinder, and by release of said pressure. The flow of compressed fluid into and out of the cylinder is controlled by suitable usual 55 means. The pressure acts upon the plastic

material at the other end or above the press-head, the material being instanced as chopped and prepared sausage meat, or as it is called, meat dough, exemplified at 14. The upward movement of the piston by means of the compressed air or water or other fluid forces the plastic material through the usual nozzle or nozzles of the stuffing machine.

The press-head as exemplified comprises a lower cylindrical section 15 and an upper cylindrical section 16. A flexible annular packing tube 17 is located between said sections at the annular outer margins of said sections. This annular packing tube is preferably resilient and composed of solid soft rubber.

The opposed annular edges of the annular margins of said sections and the respective ends of the annular packing tube are provided with complemental connections to form a tight joint between them, and to hold the annular packing tube in place. Thus the lower section 15 is provided with an annular marginal rabbet 21, the lower wall of which has an annular groove 22 therein for forming an outer annular tongue 23. The lower end of the flexible packing tube is provided with an outer annular rabbet 24 forming an inner annular tongue 25 received in the annular groove 22, the tongue 23 being received in the groove or rabbet 24.

The lower outer margin of the upper section 16 is provided with an annular rabbet 26, in the upper wall of which there is an upwardly extending annular groove 27, forming an outer annular peripheral tongue 28. The upper end of the annular flexible packing tube is provided with an outer marginal rabbet 29 to form an inner upwardly extending annular tongue 30 received in the annular groove 27, the annular tongue 28 being received in the annular groove or rabbet 29 at the upper end of the packing tube. Tongue and groove connections are thus provided between the respective ends of the flexible packing tube and the respective oppositely presented annular margins of the respective sections of the press-head.

The lower section is provided with a further annular rabbet 34, which is of less diameter than the annular rabbet 21, and is located above the latter. This annular rabbet of less diameter is within the flexible packing tube. It forms an annular wall 35, extending upwardly from the transverse wall 36.

Bracing webs 37 are located between said walls.

The lower end of the lower section is preferably provided with a cavity 39, forming an 5 annular apron 40 for said lower section. An inner annular wall 41 extends upwardly from the transverse wall 36, spaced from the annular wall 35 by an annular space 42, in which webs 43 are located connecting with 10 said annular walls and with the upper portion 44 of the transverse wall of the lower section. A passage 45 extends through the annular wall 35, connecting said space 42 and said inner annular rabbet 34 of less diameter. One or more of these passages may be provided, four of the same being shown.

The sections have slide connections between them to maintain the same in concentric and in axial relations with each other. Thus the 20 annular wall 41 forms a cylinder in which a projection 51 depending from the upper section is received, this projection being in the form of a piston or plunger having slide connection in said wall 41.

25 Means are provided for definitely adjustably positioning these sections with relation to each other. Thus a spacing-bolt 53 is threaded at 54 in the projection 51 of the upper section, the lower end of the projection 30 being the lower wall of a recess 55 in the upper end of said upper section. This spacing-bolt is provided with a bore 56. The lower end of the spacing bolt coacts with the upper face of the transverse wall of the lower section for adjustably distancing the sections 35 with relation to each other.

40 A clamping-bolt 57 is received through the bore of the spacing-bolt and is shown as a stud the lower part of which is threaded at 58 for receiving a nut 59, the bolt being fixed to the transverse wall 36 between a shoulder 60 on said bolt and said nut. The bolt has a nut 61 received over its upper threaded end, the nut coacting with the outer end of the 45 spacing-bolt for clamping the sections together at such distance apart as is determined by the adjustment of the spacing-bolt. A washer 62 is interposed between the nut 61 and the spacing bolt. The washer has an inner lug received in a slot 63 in the bolt to prevent turning of the washer. The washer is preferably a flat washer to prevent tilting strain between the bolts. The axes of the spacing-bolt and the clamping-bolt are preferably coincident with the axis of the press-head.

50 The recess 55 has an enlargement 65, in which there is a washer 66, between which and the bottom of said enlargement there is a compressible washer 67, the washers being arranged to be pressed by means of a plug 68 threaded into said enlargement, for closing the recess to leakage from the interior of the press-head.

55 The upper section comprises an upper wall

71 from the marginal edges of which an annular wall 72 depends. An intermediate annular wall 73 depends from said upper wall between said marginal wall 72 and the depending projection 51. Webs 74 connect with 70 said upper wall and said marginal wall and intermediate wall. Webs 75 connect with said upper wall and with said intermediate wall and said depending projection.

An annular compressible packing 78 is located between the sections to the inside of the annular rabbet 34. This annular compressible packing is preferably a resilient rubber ring, round in cross-section, located between said annular rabbet and the spacing-bolt, for preventing access of pressure to the spacing-bolt. This annular packing is preferably located in annular grooves 79, 80, respectively in the opposed ends of the opposed walls 35, 73, of the respective sections.

85 The adjustments of the spacing-bolt and clamping-bolt adjust the pressure exerted upon the annular packing 78 and also adjust the pressure in axial direction exerted upon the annular packing tube 17. These adjustments permit pressures to be applied to the annular packing and to the annular packing tube according to the fluid pressure used, and to compensate for wear and change in 90 and deterioration of materials.

95 During operation of the stuffing machine, when fluid pressure is applied under the press-head to raise the press-head, compressed fluid also passes through the passages 45 into the annular space within the annular packing tube 17, for pressing said annular packing tube throughout its circumference radially outward and causing it to tightly hug the wall of the cylinder for forming a close slip fit with said wall and preventing 100 passage of compressed fluid past the press-head into the body of material thereabove, this pressure also causing the tongues of the packing tube to be pressed against the tongues 105 on the sections for insuring closing of the 110 joint between said sections.

115 The annular packing ring 78 is preferably distanced radially from the adjusting bolts, so as to avoid distribution of said compressed fluid throughout a large portion of the space 120 between the sections of the press-head, in order that ready release of said pressure within the annular packing tube 17 may be had upon relief of pressure under the press-head, for quick inward movement or straightening of said annular packing tube to enable 125 the press-head to readily descend by gravity in the cylinder.

130 The adjustable means for adjusting the space between the sections of the press-head enables such adjustments to be obtained without taking said sections apart, mere removal of the plug 68 and washers 66 and 67 permitting access to the head of the spacing-bolt 53 and to the nut 61 by means of suitable

socket wrenches for ready adjustment of the same, the resilient annular packing ring 78 automatically maintaining a barrier or close joint between said sections surrounding the 5 adjusting means throughout the adjustments of said adjusting means.

Having thus fully described my invention, what I claim as new, and desire to secure by Letters Patent, is:

- 10 1. A press-head comprising an upper section and a lower section in axial alinement with each other, a flexible annular packing tube between the opposed outer marginal edges of said sections, said opposed outer 15 marginal edges of said sections and the respective ends of said packing tube provided with complemental connections, an adjustable hollow spacing-bolt between said sections and an adjustable clamping-bolt in the 20 hollow of said spacing-bolt for adjustably clamping said sections together, the axes of said bolts being substantially coincident with the axis of said press-head.
2. A press-head comprising an upper section and a lower section in axial alinement with each other, a flexible annular packing tube between the opposed outer marginal edges of said sections, said opposed outer marginal edges of said sections and the respective ends of said packing tube provided with complemental connections, an adjustable hollow spacing-bolt between said sections and an adjustable clamping-bolt in the hollow of said spacing-bolt for adjusting the 30 axial distance between said sections, the axes of said bolts being substantially coincident with the axis of said press-head, an annular space between said sections within said cylindrical packing tube, said press-head arranged to be raised by compressed fluid thereunder, said lower section provided with a passage communicating with said compressed fluid and with said annular space for expanding said flexible annular packing tube during application of such pressure to said press-head, and a compressible annular packing between said sections located between said annular space and said spacing-bolt and automatically yielding to the adjustments of said 45 bolts for being continuously clamped between said sections throughout said adjustments.
3. A press-head comprising an upper section and a lower section in axial alinement with each other, said lower section provided with an upwardly extending cavity, an annular packing tube between said sections at the outer margins of said sections, said outer margins and the respective ends of said annular packing tube provided with complemental connections, an adjustable spacing- 50
- 55 bolt provided with an axial bore between said sections and a clamping-bolt in said bore whereby to adjustably fix the distance between said sections and clamp said sections together in adjusted relations, said lower section provided with an annular peripheral rabbet inside said annular packing tube, said lower section provided with a passage communicating with said cavity at one of its ends and with said annular rabbet at its other end for transference of pressure from said cavity into said annular rabbet and the exertion of outward pressure upon said flexible packing tube, and an annular compressible packing between said sections and between 60 said annular rabbet and said spacing-bolt arranged to be adjustably compressed between said sections by the adjustments of said spacing-bolt and said clamping-bolt for automatically maintaining a close joint between 65 said sections surrounding said bolts throughout said adjustments.
4. A press-head comprising an upper section and a lower section in axial alinement with each other, each of said sections provided with an annular rabbet and an annular groove at the inner portion of said rabbet forming an annular tongue outside said annular groove, said annular rabbets, annular grooves and annular tongues on said respective sections presented toward each other, one of said sections further provided with an annular rabbet of less diameter than the diameters of said first-named annular rabbets, an annular flexible packing tube between said sections whose respective ends are formed complemental to and coat with said respective first-named annular rabbets, annular grooves and annular tongues, said lower section arranged for having compressed fluid applied thereagainst for raising said press-head, said lower section provided with a passage communicating with said compressed fluid and with said annular rabbet of less diameter for exerting outward pressure upon 70 said annular flexible packing tube, a central spacing-bolt having a bore and a central clamping-bolt between said sections to adjustably fix the distance between said sections, said clamping-bolt located in said bore of said spacing-bolt, and an annular compressible packing between said sections and between said spacing-bolt and said annular rabbet of less diameter arranged to yield and accommodate itself to the varying distances between said sections due to the adjustments of said spacing-bolt and said clamping-bolt.
- 80 In testimony whereof, I have hereunto signed my name.

OSCAR C. SCHMIDT.
